CLAIM

The ornamental design for cigarette case, as shown and described.

DESCRIPTION

1. Cigarette case

Figure 1.1 is a front, left side perspective view of a cigarette case showing the new design;

Figure 1.2 is a left side elevation view thereof;

Figure 1.3 is a right side elevation view thereof;

Figure 1.4 is a rear elevation view thereof;

Figure 1.5 is a top plan view thereof; and

Figure 1.6 is a bottom plan view thereof.

The broken lines shown in the drawings illustrate portions of the cigarette case that form no part of the claimed design.
